UNITED STATES PATENT OFFICE.

ELZA M. PRING, OF ALLEGANY, OREGON.

SAW-JOINTER.

1,116,842.

Specification of Letters Patent. Patented Nov. 10, 1914.

Application filed May 5, 1914. Serial No. 836,469.

To all whom it may concern:

Be it known that I, ELZA M. PRING, citizen of the United States, residing at Allegany, in the county of Coos and State of Oregon, have invented certain new and useful Improvements in Saw-Jointers, of which the following is a specification.

My invention relates to saw jointers and the primary object of the invention is the provision of a jointer so constructed that it will joint the cutting teeth of a saw to a uniform length transversely thereof.

A further object of the invention is to so construct the jointer that it will give a uniform and predetermined curve to the edges of teeth of cross cut saws.

A further object of the invention is to provide a jointer so constructed that a file may be readily applied thereto or removed therefrom, and to provide means whereby the file may be curved to any predetermined degree.

Still another object is to provide a saw jointer of such simplicity of construction that it may be cheaply manufactured and readily used.

Other objects will appear in the course of the following description.

My invention is illustrated in the accompanying drawings wherein:

Figure 1 is a front elevation of a saw with my improved saw jointer mounted thereon. Fig. 2 is a perspective view of the saw jointer. Fig. 3 is a sectional view on the line 3—3 of Fig. 1. Fig. 4 is a perspective view of a file adapted to be used with my jointer.

Corresponding and like parts are referred to in the following description and indicated in all the views of the accompanying drawings by the same reference characters.

Referring to these figures, it will be seen that my improved jointer comprises a frame or stock 2 of any desired length, preferably slightly greater in length than the length of the file used with the jointer. This frame 2 is of openwork or skeletal form and is preferably cast and at its upper end is formed with the inwardly projecting flange 3. The ends of this flange are formed with

downwardly turned extremities 4 adapted to engage over the extremities of the file used and just inward of these extremities the flange is formed with the shoulders 4^a against which the ends of the file rest. The middle of the flange is upwardly offset as at 5 to form a bridge. Through this middle upwardly bowed portion 5 is a screw threaded perforation 6 for engagement with a screw shank 7.

The inner face of the frame 2 is provided with the laterally projecting flanges or ribs 8 and the inwardly projecting flanges or ribs 9. The ribs or flanges 8 are in alignment with each other but the inner ends of the flanges are spaced from each other. The flanges 9 are also in alignment with each other and in vertical alignment with the flanges 8. These flanges 8 and 9 project inward to a plane extending through the middle plane of the back or flange 3.

Swiveled to the screw 7 is a file clip 10 which as shown in Fig. 3 has downwardly extending ends 11 with inwardly turned extremities 12 adapted to engage beneath the marginal edges of the file 13. The file 13 as illustrated in Fig. 1 is just long enough to rest upon the shoulders or abutments 4^a and to be engaged at its ends by the hook-shaped extremities 4. The middle of the file is engaged by the clip 10.

Mounted upon the screw 7 is the wing nut 14 and when this wing nut is turned in one direction it will act to draw upward on the screw 7 thus causing the clip 10 to be drawn inward or toward the portion 5 and acting to bend the middle of the file. As the ends of the file engage with the shoulders 4^a, it will be obvious that the file will be bowed and that the degree of curvature of the file will depend upon the extent to which the nut 14 is turned up. Thus this degree of curvature may be very delicately adjusted and thus the file may be adjusted to suit the curvature of any cross cut saw.

In actual use the saw 15 is placed within a vise (not shown) and of any suitable character and with the teeth upward. The jointer is then disposed with the flanges 8 and 9 against the saw and with the file en-

gaging the toothed edge of the saw. The jointer is then reciprocated to file the edge. Inasmuch as the file is curved by the bowing of its middle portion, it is obvious that the teeth engaged by the file will be likewise curved. As the frame 2 holds the file exactly at right angles to the saw, it will be obvious that the teeth will be filed uniformly transverse to the length of the saw.

10 The frame of the jointer is of such construction that it may be readily cast and thus may be cheaply made. It will also be seen that exclusive of the file there are only three pieces to the jointer, two of these being an ordinary bolt and nut.

15 The teeth of the file 13 do not extend the full length of the file but the end portions 16 of the file are devoid of teeth. The smooth surface at each end of the file is for 20 the purpose of regulating the cutting of the file. By reason of the fact that the ends are smooth surfaced and that the curvature of the file can be increased or decreased by the thumb screw, the file can be adjusted 25 so as to cut very lightly on the points of the saw teeth and prevent it from cutting away any portion of the saw teeth unnecessarily and to no purpose. My jointer permits a 30 file to be used for about twice the length of an ordinary jointer. Thus I can secure a true circle for the entire length of the file, thus enabling the raker gage to work more accurately, and also so jointing the saw 35 that it will run smoother and do more work before the teeth require rejointing. The length of the file causes it to work more accurately than if the file were short.

What I claim is:

1. A saw jointer comprising a frame having inwardly projecting ribs adapted to contact with the side of the saw and an inwardly projecting flange extending along its upper edge, the middle of said flange being upwardly bowed, the ends of the flange 40 being formed with downwardly extending abutments, a screw passing through the upwardly bowed portion of the flange, a nut engaging the screw, and a file engaging clip swiveled upon the lower end of the screw.

50 2. A saw jointer comprising a frame having inwardly projecting ribs and an inwardly projecting flange extending along its upper edge, the ends of the flange being formed with downwardly extending abutments and the middle of the flange being upwardly bowed, a screw passing through the upwardly bowed portion of the flange 55 a nut engaging the screw, a file engaging clip swiveled upon the lower end of the screw, and a file bearing at its ends against the abutments and at its middle engaged with said clip.

60 3. A saw jointer comprising a skeletal

frame having upper and lower pairs of inwardly extending ribs, the pairs of ribs being longitudinally spaced from each other, said frame also having an inwardly projecting flange extending along its upper edge, the middle of the flange being bowed and the ends of the flange being formed with 70 downwardly extending abutments, a screw passing through the middle of the flange, a nut engaging the screw, a file engaging clip swiveled upon said nut and having inwardly extending extremities, and a file engaging at its ends against the abutments and at its middle engaged by said clip. 75

4. A saw jointer comprising a frame having a plurality of pairs of longitudinally extending inwardly projecting integral 80 ribs, the pairs of ribs being longitudinally spaced from each other, said frame also having an inwardly projecting longitudinally extending integral flange at its upper end, the middle of said flange being upwardly bowed and perforated, a screw passing through the perforation of the flange, a nut engaging the screw, a U-shaped file engaging clip swiveled upon the screw and having inwardly turned extremities, and a 90 file bearing at its ends against the abutments, the middle of the file being engaged by said clip.

5. A saw jointer comprising a frame having inwardly projecting ribs adapted to contact with the side of a saw and an inwardly projecting flange extending along its upper edge, the extremities of the flange being downwardly extended to engage over a file and being formed with seats supporting the 100 extremities of the file and engaging the ends of the file to prevent longitudinal movement thereof, a file resting at its extremities upon said shoulders, and means at the middle of the frame engaging the middle of the file and bowing it inward. 105

6. A saw jointer comprising a file supporting frame, the ends of the frame being formed with shoulders projecting from the frame for supporting the extremities of a 110 file, the middle of the frame having means for engaging the middle of the file and bowing it inward, and a file supported by said frame, said file having plane faced ends, the middle portion of the file being formed 115 with cutting teeth.

7. A saw jointer comprising a frame having inwardly projecting ribs and an inwardly projecting flange or back extending along its upper edge, the ends of the flange 120 having file supporting shoulders and the extremities of the flange being formed with hooks engageable over the ends of a file, the middle of the flange being upwardly bowed, a screw passing through the upwardly 125 bowed portion of the flange, a nut engaging

the screw, a file engaging clip swiveled upon the lower end of the screw, and a file bearing at its ends against the shoulders and supported from longitudinal movement by the hooks, the middle of the file being engaged by said clip, the ends of the file being plane faced.

In testimony whereof I affix my signature in presence of two witnesses.
